UNITED STATES PATENT OFFICE.

OSWALD LUSCHNIG, OF NOKOMIS, ILLINOIS.

POWER COAL SHOVEL.

Application filed February 28, 1925. Serial No. 12,308.

To all whom it may concern:

Be it known that I, OSWALD LUSCHNIG, a citizen of the United States, residing at Nokomis, in the county of Montgomery and State of Illinois, have invented certain new and useful Improvements in Power Coal Shovels, of which the following is a specification.

This invention relates to new and useful improvements in power coal shovels.

The primary object of my invention is to provide a shovel for loading coal excavated in mines into the cars, instead of employing manual labor for this purpose. With the use of my device it will not be necessary to load the coal into the cars by manual labor in the ordinary way but merely to loosen the coal, when the shovel will be the work ordinarily performed by ten men.

With the foregoing and other objects in view that will appear as the nature of my invention is better understood, the same consists in the novel features of construction, combination and arrangement of parts illustrated in the drawings and more particularly pointed out in the appended claims.

In the accompanying drawings, which are for illustrative purposes only and are therefore not drawn to scale:

Figure 1 is a top plan view of a power coal shovel embodying my improvements.

Figure 2 is an end view.

Figure 3 is a side view.

Figure 4 is a vertical transverse section, taken through the lower end of the chute and its supporting means, with the parts represented on an enlarged scale.

Figure 5 is a central longitudinal enlarged sectional view of the lower end of the chute.

Figure 6 is a detail plan view of the cam roller and associated parts, and

Figure 7 is a detail fragmentary transverse sectional view of the cam roller and associated parts.

Referring to the drawings for a more particular description of my invention and in which drawings like parts are designated by like reference characters throughout the several views, A represents the base provided at one end with a supporting frame 1 comprising the spaced standards 2. The base A is revolvably mounted by means of the turn table B on a low truck C in order that the base may be turned to reach coal from all sides. A U-shaped hinge

member 3 is hingedly connected at its ends 4 in the eyes 5 of suitable bearings 6 mounted on the upper ends of the standards 2. The horizontal central or intermediate portion 60 of the hinge member 3 extends under and supports the upper end of the chute 8. The chute 8, which is preferably of U-shape form in cross section, extends at right angles to the plane of the base A and extends 65 downwardly from the base at a suitable inclination. The lower end of the chute is mounted on and operatively supported by the lower ends of angle bars 10 fastened at their upper ends to the top of the base A, 70 and in provided with a suitable shovel 11, which is pivotally connected at its inner ends by the transverse bolts 11', to the lower end of the chute and may be adjusted at the desired angle by tightening up the wing 75 nuts 12'. A horizontally disposed lever 12 is fulcrumed intermediate its ends on the bearing post 13 rigidly mounted on the base and is connected at one end by means of the connecting rod 14, cross rod 15 and ears 16 80 to the lower end of the chute. The opposite end of lever 12 is provided with a downwardly projecting pin 17 which works in a cam groove 18 having a substantially V-shape portion 19 formed in the periphery of 85 the roller 20, journaled in suitable bearings 21 mounted on the adjacent end of the base A. One end of the shaft 21 of the roller 20 is provided with a pulley 22 over which a belt (not shown) is adapted to pass in driv. 90 ing the roller by power.

In practice, power is applied to drive the roller 20 which by virtue of its V-shaped cam groove causes the chute and shovel to reciprocate back and forth with a quick 95 jerky movement, which constantly forces the coal up until it reaches the upper end of the chute and falls into the waiting coal car. Attention is invited to the fact that the shovel is made from a single 100 piece of metal bent or folded back upon itself intermediate its ends to form a transverse shoulder or ridge 23 which not only aids in forcing the coal up the chute but acts as a catch in preventing any of the 105 coal from slipping back.

The several parts of my device may be of any desired size or dimensions and of any suitable material.

From the foregoing description, taken in 110 connection with the drawings, it is thought that the construction, operation and advan-

tages of my invention will be readily understood without requiring a more extended explanation.

Having described my invention, what I claim as new and desire to secure by Letters Patent, is:—

1. A power coal shovel comprising a base, an upwardly inclined chute extending at right angles to the plane of the base and 10 hingedly supported at its upper end upon the latter, means for operatively supporting the lower end of the chute, means for reciprocating the chute back and forth and a shovel hingedly connected to the lower end 15 of the chute, said shovel formed from a single piece of metal bent or folded back upon itself at a point intermediate its ends to form a transverse shoulder or ridge, substantially as and for the purpose specified.

2. A power coal shovel comprising a base, 20 an upwardly inclined chute extending at right angles to the base and hingedly supported at its upper end upon the latter, means for operatively supporting the lower end of the chute, a shovel hingedly connected to the lower end of the chute and 25 means for reciprocating the chute and shovel back and forth, said means comprising a lever fulcrumed to the base and connected at one end with the chute, a roller journaled on the base and formed in its periphery with a V-shaped cam groove and a pin carried by the adjacent end of the lever and working in said groove.

In testimony whereof I affix my signature. 35

OSWALD LUSCHNIG.
